UNITED STATES PATENT OFFICE.

WILLIAM M. BONWILL, OF CAMDEN, DELAWARE.

HERNIAL TRUSS.

Specification of Letters Patent No. 12,266, dated January 23, 1855.

To all whom it may concern:

Be it known that I, WILLIAM M. BONWILL, of the town of Camden, Kent county, and State of Delaware, have invented a new 5 and Improved Truss for the Two Inguinal and the Umbilical Hernia; and I do hereby declare that the following is a full and exact description thereof, reference being had to the accompanying drawings and to the letters of reference marked thereon.

The nature of my invention and improvement consists in combining in one truss, a single, a double, inguinal, and an umbilical truss, which may be used advantageously for 15 either alone or for the three combined.

First, I construct a circular hoop made of steel which passes around the waist of the patient between the top of the hips and the bottom of the lower ribs, see letters A, A, 20 A, A, as far front as the front part of the hips B, B, thence bending in a curve at B, B, and passing down in front to the groins opposite to the ruptured parts or internal abdominal rings at C, C, with two 25 extra holes D, D, with a hinge F, in the middle of the back of the hoop at E, E, with two extra holes G, G. Thus I describe the entire hoop of my truss. The hoop is divided at E, E, into two equal parts, to be 30 joined together again by the hinge F by 4 screws, O, O, O, O, making the entire hoop complete. I shall now speak of this hoop as a truss. The strop I, passing from H, to H, across or over the navel of the patient 35 horizontally, to which the pad K, is fixed or attached forming the truss for umbilical hernia and the pad K, is to be used in a case of that kind, the strop I, binding the truss firmly together around the waist. The strop 40 L, passes horizontally across the groins of the patient at the pads M, M, to prevent the truss from opening too much in case of a violent strain letting the bowels pass out, thus making the truss almost immovable, 45 while other trusses now in use will be slipping out of place and throwing the pad off the rupture and the bowels escaping out. The great superiority of this truss over all others, consists in that of its passing around 50 the waist of the patient as before described, affording a great support to the ruptured parts, and to the adjacent parts generally by the strops I, and L, binding the truss firmly together, preventing the truss from 55 moving either way. The use of the hinge F, is a matter of convenience in putting on

and taking off, preventing also the hoop from being strained too much, and also making it fit the more easily. The two extra holes in the hinge F, at G, G, are for the 60 purpose of making the hoop larger to suit the case. The front part of the hoop C, C, passing down opposite to the abdominal rings and is supported by the truss extending around the waist, the hinder part of the 65 truss N, N, resting against the back of the patient making a fulcrum while the front of the hoop C, C, forms the lever. The two extra holes D, D, in the point of the hoop are used to make the truss larger. The two 70 pads M, M, which are attached to the end of the hoop C, C, are so formed and placed as to press on the internal abdominal rings, thence directly down over the canal and bears firmly upon said external rings, preventing 75 the bowels from passing down. The pads M, M, are both to be used in a single as well as in a double inguinal hernia. I have tried a single pad on one side of the 80 hoop at C, and find that it will not answer so well, owing to the leverage at C, being on one side only it is apt to twist the truss around off the rupture. The double pads are therefore more pleasant to wear, and the 85 leverage in the double pads is equal on both sides, which prevents the truss from being moved without great force from its place. Thus this truss may perform, if occasion requires, the office of the three trusses consolidated into one. This as it is said by Professor 90 Gibson of the Pennsylvania University and others has never been done before. It has been thought that pressure made upon the spermatic veins is the most ready way to cure cirsocoele, a disease of the spermatic 95 veins. If so this apparatus will form the most easy yet permanent support or pressure ever yet invented or used. The pads M, M, rest directly over and upon the spermatic veins or cord in the same manner as 100 when used in hernia on either or both sides.

Another great advantage in this truss is that the whole hoop may be made of untempered steel, owing to its great length yielding so regularly. This, from its location, 105 will prevent the hoop from all danger of breaking. It may possibly however in very violent strains or falls become bent, but it may be easily replaced to its proper shape and office—another advantage over all 110 others in use. Other trusses from the shortness of their spring and from their loca-

tion (being worn around the pelvis) and from their being made of so high tempered a material, are constantly liable to be broken and often are broken. This truss of mine 5 affords a pleasant support to the back of the patient and to the ruptured parts, and to all the adjacent parts generally. Any person having once worn one of my trusses will never wear any other in use. I have myself 10 worn several kinds of trusses, but always found the best of them exceedingly unpleasant and bungling, very hard to keep in place, not keeping the bowels up nor answering as they should do the purpose intended. This same complaint has been general by others who have worn them so far 15 as my knowledge both as a practitioner and a close observer extends. These considerations induced me to endeavor to obviate the aforesaid difficulties. The drawing before 20 you exhibits a truss which exactly meets the case. It is an original idea of my own, sug-

gested by personal necessity. I have never seen, heard or read of anything like this truss, until I made it. I have worn one of 25 these trusses for three years, on my own person, with the greatest pleasure and with the greatest alleviation of personal suffering.

I do not claim the hinges F, F, the adjustability of the pads, or the form of the 30 hoop, separately, but what I do claim and desire to secure by Letters Patent of the United States, is,

The combination of the peculiarly formed hoop with the umbilical pad and strap, for 35 the purpose of preventing the movements of the body from displacing the pad in either umbilical or in inguinal hernia as set forth.

Camden, Del., May 14/53.

WILLIAM M. BONWILL.
